UNITED STATES PATENT OFFICE.

FRITZ RITTER VON DORMUS, OF FLORIDS DORF, AUSTRIA-HUNGARY.

LOCOMOTIVE FIRE-BOX.

SPECIFICATION forming part of Letters Patent No. 516,923, dated March 20, 1894.

Application filed June 17, 1893. Serial No. 477,951. (No model.) Patented in England April 9, 1892, No. 6,858; in France April 9, 1892, No. 220,800; in Belgium April 11, 1892, No. 99,185; in Switzerland October 15, 1892, No. 5,282, and in Austria-Hungary November 6, 1892, No. 4,148 and No. 59,916.

To all whom it may concern:

Be it known that I, FRITZ RITTER VON DORMUS, engineer, residing at Floridsdorf, near Vienna, in the Empire of Austria-Hungary, have invented certain new and useful Improvements in Locomotive Fire-Boxes, (for which I obtained a patent in England April 9, 1892, No. 6,858; in France April 9, 1892, No. 220,800; in Belgium April 11, 1892, No. 99,185; in Switzerland October 15, 1892, No. 5,282, and in Austria-Hungary November 6, 1892, No. 4,148 and No. 59,916,) of which the following is a true, correct, and complete specification.

15 In the drawings:—Figure 1, is a part of a boiler showing the fire box in section. Fig. 2, is a rear view showing the shells of the boiler and fire box and the connecting brace between. Fig. 3, is a detail sectional view.
20 The fire box is surrounded by the jacket of the boiler between which the water circulates and this box is open in the rear for its entire height and breadth. The upper and side walls of the jacket of the boiler are connected with the upper and side walls of the fire box by means of the interposed bow piece *a*, and this piece and the walls are still further stayed by means of cross bars *b* and *c*, the latter serving at the same time as a support 25 for the rear end of the grate. A water box *d* is inserted in the rear of the box at the upper end covering the entire breadth of the fire box and protruding into the fire room. This water box communicates with the main 30 boiler by the tube *e* through which the steam coming from the water box issues into the main boiler and on the other side by the tube *f* through which the water of the main boiler passes into the water box *d*. These tubes 35 and the connecting pieces by which they are fixed to the boiler and water box, are located outside of the fire box. The water box can be easily cleaned by means of large and small openings *g* suitably closed. The opening to 40 the fire box located above the water box *d* is closed by a plate *h* provided with an opening (not shown) that can also be closed through which the fire tubes can be inspected. Within 45 the box is a fire screen *i* made of a fire proof material projecting from the rear wall 50

of the fire box and this screen extends upwardly as shown in Fig. 1, at an inclination.

The grate *k* located underneath the water box and fire screen is inclined to the front so that the coal that is upon it feeds forward 55 and requires but little assistance of the fireman. The grate is located so high that the fire can be observed and regulated through a floor *l* opening above the platform, said door *l* is open during the travel and can be closed 60 entirely or partly for decreasing the combustion.

In order to form a rest for the poker or rod for stirring the fire, I arrange a cross piece *m* below the grate. The grate *k* is toothed or 65 corrugated in its upper part and smooth in its lower part as at *s*. A hinged grate *n* is disposed at the lower end of the grate *k* which can be opened downward from the supporting board in order to remove the clinkers or 70 ashes.

Under the water box *d*, a fire chest is disposed that closes the rear opening of the fire box and is provided with two openings closed by doors *o*, *p*. The lower opening reaches 75 over the entire breadth of the fire box and has a door *o* which opens to the inside and can be fixed in any desired position by means of a lever and toothed segment (not shown). The door forms with the bottom plate of the 80 fire chest a funnel shaped opening through which the coal is carried upon the grate. The upper opening *p*, does not need to extend over the entire breadth of the fire box as it serves for the admission of air for the 85 combustion. The coal is carried into the space *q* and feeds forward in the proportion that the combustion proceeds upon the grate, is converted into gas in the space *r* between the water box and the grate and reaches 90 finally the part *s* of the grate where it burns in the shape of coke. The gases that rise at *r* are carried from the water box into the space *t* where they mix with the gas generated at *s* and are burned completely. Back 95 under the water box in a protected position flat jets of steam can be pressed forward by means of steam pipes (not shown) in order to cause a more intimate mixing of the different gases in the space *t*. In this construction the 100

combustion is continuous and all the disadvantages of a periodical heating and the disadvantages caused by the opening of the fire box door (consisting especially therein that 5 the great quantity of inflowing cold air disturbs the combustion and that the boiler suffers by those sudden changes of temperature) are avoided. The single stages of the combustion are such that a most complete combustion is secured with a minimum excess of air.

I claim—

1. A boiler having a fire box and a bow piece *a* interposed between the boiler jacket 15 and the fire box shell, substantially as described.
2. In combination with a boiler, a fire box having an inclined grate and a dumping section, a fire chest located at the upper end of 20 said grate having a lower fuel opening and

an upper air inlet, a vertically arranged inwardly swinging door closing the fuel opening, and an inclined outwardly swinging door closing the air inlet, substantially as described.

3. In combination with the boiler, the fire box having an inclined grate, the inclined screen *i* located above said grate, and the inclined water box located in rear of the screen and having a space between their adjoining edges for the products of combustion, and steam and water connections from the rear of the water box around the fire box to the sides of the boiler, substantially as described. 30

In witness whereof I hereunto set my hand 35 in presence of two witnesses.

FRITZ RITTER VON DORMUS.
